Primary Examiner — Dana K Weiland*Assistant Examiner* — Jenny lou M Binas(74) *Attorney, Agent, or Firm* — Birch, Stewart, Kolasch & Birch, LLP(57) **CLAIM**

We claim the ornamental design for a hanger for ironing board, as shown and described.

DESCRIPTION

FIG. 1 is a perspective view of a hanger for ironing board showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view showing a state of use thereof.

The broken line showing of the ironing board in FIG. 8 is for the purpose of illustrating environmental structure and forms no part of the claimed design.

1 Claim, 8 Drawing Sheets(56)
